(57) **CLAIM**

The ornamental design for a head torch, as shown and described.

DESCRIPTION

FIG. 1 is a front perspective view of a head torch showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof; and,

FIG. 7 is a side view thereof.

The broken lines illustrate structure or features which form no part of the claimed design.
